AUTOMATIC VOLUME CONTROL CIRCUIT

Reginald Basil Armstrong, London, England, assignor to Radio Corporation of America, a corporation of Delaware

Application November 10, 1932, Serial No. 641,957
In Great Britain December 2, 1931

10 Claims. (Cl. 250—20)

This invention relates to thermionic amplifiers and more particularly to thermionic amplifiers of the kind wherein means are provided for automatically controlling the "gain" of the amplifier 5 in such manner that the "gain" is increased for weak received signals and decreased for strong received signals. Such amplifying arrangements, which may be termed "automatic gain controlled amplifiers" are well known and are used for various purposes, one of the principal purposes being to reduce, at a receiver, the effects of fading.

The present invention has for its object to provide an improved automatic gain controlled thermionic amplifier which shall be of very simple 15 construction and in which a large degree of control is obtained in a simple and efficient manner.

According to this invention automatic gain control in a thermionic amplifier is effected by utilizing varying voltage drop set up in an impedance whose effective resistance is caused to vary in dependence upon received signal strength, to vary one or more of the control potentials applied to an amplifier valve. The amplifier valve whose gain is controlled in this way may be of any 20 known suitable construction, e. g., it may be a triode or a screened grid valve.

The impedance whose effective resistance is caused to vary in dependence upon received signal strength may conveniently include or be constituted by the anode-cathode path of a thermionic valve whose internal resistance is automatically varied in dependence upon received signal strength and the voltage across which may be directly applied without further amplification 25 to control the amplifier gain.

The invention is illustrated in the accompanying diagrammatic drawings.

Figure 1 shows a basic form of the invention, Figure 2 shows a modification of the arrangement 40 in Figure 1,

Figure 3 shows a modification of the arrangement in Figure 2,

Figure 4 shows another modification of the arrangement in Figure 1,

Figure 5 shows a modification of the circuit in Figure 4,

Figure 6 shows another modification of the circuit in Figure 4,

Figure 7 shows a modification of the circuit in Figure 6,

Figure 8 shows another modification of the circuit in Figure 1,

Figure 9 shows a modification of the circuit in Figure 8,

Figure 10 shows a modification of the circuit in Figure 8,

Figure 11 shows a modification of the circuit in Figure 9.

Referring to Fig. 1, which shows one way of carrying out the invention as applied to the control of the gain of a radio frequency thermionic amplifier valve of the screened grid type, a tuned input circuit consisting of inductance 1 and tuning condenser 2 is connected between the control grid 3 and the cathode 4 of the screen grid valve 5. One end of said circuit is directly connected to the control grid, and the other end is connected through a condenser 6 to the cathode. The anode 7 of the valve 5 is connected through the usual output coupling impedance (which may consist, as shown, of the primary 8 of a transformer whose secondary 9 is tuned by a condenser 10 and connected to the next stage which is not shown) to the positive terminal HT+ of a source 10 of anode potential.

This source is shunted by a circuit consisting of two resistances 11 and 12 in series, the second resistance 12 being so arranged, or constituted, that its effective resistance increases with increase 15 of the strength of the received signal. In addition to being so arranged, or constituted, as to vary in value with signal strength, the second resistance may also, if desired, be manually adjustable in value. The junction point 13 of the two resistances is connected to the cathode of the valve, while a suitable tapping 14 on the resistance 11 is connected to the screen grid 15. A condenser 16 is shunted between this tapping point and the cathode, and a connection is taken 20 from the cathode end of the input tuned circuit (which end is separated from the cathode by the condenser 6) to the negative terminal HT- of the source of anode potential.

It will be seen that with this arrangement the 40 amplification gain will vary in an inverse direction with the strength of input signals. This variation of amplification gain is due to the fact that the grid bias applied to the control grid of the screened grid valve will depend upon the 45 voltage drop across the resistance 12 which, in turn, is made to increase with increase in the strength of the received signal. A further effect resulting in change of amplification is that the effective anode potential applied to the anode of 50 the screened grid valve will vary.

This is so since the sum of the voltage drops across the two resistances 11 and 12 must always be equal to the high tension voltage i. e., since $V_2 + V_3 = V$ (see Fig. 1) an increase in poten- 55

- tial drop across the resistance 12 must be accompanied by a decrease in potential drop across the resistance 11. A yet further effect is that, since the ratio of the voltage between the cathode and the screen grid to the voltage between the cathode and the positive terminal of the high tension source is constant i. e., since the ratio of V_1 to V_2 is constant (see Fig. 1), the screen grid voltage will vary in sympathy with the anode voltage.
- 10 In a practical embodiment the resistance 12 of Fig. 1, described as increasing in effective value with increase in received signal strength, is constituted by, or includes, the anode-cathode path of a thermionic valve. In this arrangement, 15 which is illustrated in Fig. 2, the input tuned circuit 1, 2, is connected at one end to the control grid 3, and at the other to a positive point $+HT2$ on the high tension source. The anode 7 of the screened grid valve is connected through 20 the primary 8 of a coupling transformer, and thence through a resistance 11, to the cathode 4, the junction point 17 of the primary 8 and resistance 11 being connected to a tapping point $+HT3$ on the high tension source more positive 25 than the point $+HT2$. The screen grid 15 is connected to a tapping point 14 upon the resistance 11, which tapping point 14 is connected through a condenser 16 to the cathode.
- The cathode 4 is, also, connected to the anode 30 18 of a second valve 19 whose cathode 20 is connected through a suitable condenser 21 to the cathode of the screened grid valve, and, also, to a positive point $+HT1$ in the high tension source which is negative with respect to the point $+HT2$.
- 35 The control grid 22 of valve 19, which is a triode, is connected through a second resistance 23 and suitable bias battery (not shown), if desired, to the negative terminal $HT-$ of the high tension source, and, also, to the cathode 24 of a detector valve 25. The latter is coupled to the output circuit of the screened grid valve through the coupling transformer, as shown, said second valve being arranged to act as a detector, for 40 example, by the method of cumulative grid rectification. The output of the detector valve is connected, or coupled, to a utilization circuit, or to one, or more, subsequent amplifiers as may be required. The input circuit of the detector valve consists of the usual tuned input circuit 9, 10, which is connected at one end of the grid 28 through a grid condenser 26, and at the other to the cathode, a grid leak 27 being connected between the grid and the cathode.
- 45 It will be seen that with this arrangement, so long as no signal is received, the grid bias on the detector valve will be zero. It will, therefore, pass anode current which will apply a positive potential to the grid of the valve 19. This positive potential is prevented from acting as bias by reason of an equal potential which is applied to the cathode of said valve 19 so that in the condition of zero received signal, the grid bias in the second valve is zero. The valve 19 will accordingly pass anode current, and there will be a substantial voltage drop between the anode and cathode therein.
- 50 This drop of voltage applies a positive potential to the cathode of the screened grid valve, and, accordingly, the point $+HT2$ to which the input circuit of the screened grid valve is connected is so chosen that the control grid of the screened grid valve is negative with respect to the cathode thereof by an amount equal to a desired normal working bias. When signals are received the anode current of the detector valve decreases,

the positive potential on the grid of the valve 19 is accordingly decreased, the internal impedance of the said valve 19 increases, and a control of the amplification of the screen grid valve is effected in a manner closely analogous to that previously 5 described in the specification.

In a further modification of the last mentioned arrangement and illustrated in Fig. 3 the detector valve is connected as in the usual way, and an auxiliary detector is employed for controlling the internal impedance of the second valve to produce automatic gain control in dependence upon received strength. In this modification, the tuned input circuit 1, 2, for the screened grid valve is connected at one end to the control grid 15 3, and at the other to a positive point $+HT2$ on the high tension source and through a condenser 6 to the cathode 4. The anode circuit of the screened grid valve is as described in the last mentioned embodiment, the screen grid deriving 20 potential from the resistance 11 as described in connection with the said embodiment.

A detector valve 25 is coupled in cascade to the output circuit of the screened grid valve, the tuned input circuit 9, 10 of said detector being 25 connected between the control grid 28 thereof and the negative terminal $-GB$ of a grid bias battery (not shown) whose positive terminal $+GB$ is connected to the negative terminal $HT-$ of the high tension source. The output circuit 30 of this detector is coupled to a succeeding stage or to a utilization circuit in the customary manner. An auxiliary detector 31 is provided, and the grid 32 of this auxiliary detector is capacitatively coupled by condenser 33 to the grid 28 of 35 the first detector 25, a grid leak 34 being connected between the grid of the second detector and the cathode thereof as in the usual way.

The anode 35 of the second detector is connected to a suitable point $+HT3$ on the source 40 of high tension potential. The cathode of the second detector is connected to the control grid 22 of a second valve 19 which serves the same purpose as the second valve 19 in the last described embodiment, said control grid being connected through a resistance 23 and bias battery, if required, (not shown) to the negative terminal of the high tension source. As before, the cathode of the screened grid valve is connected through a condenser 21 to the cathode 20 of the 50 second valve 19 which is in turn connected to a point $+HT1$ on the high tension source less positive than the point $+HT2$.

In another modification of the invention as applied to a radio frequency thermionic amplifier, 55 and illustrated in Fig. 4, a screened grid valve 5 has a tuned input circuit 1, 2, connected between its control grid 3 and cathode 4, one end of said circuit being directly connected to the control grid and the other end being connected through 60 a condenser 6 to the cathode. The anode 7 of the valve is connected through the usual output coupling impedance (which may consist as shown of the primary 8 of a transformer whose secondary 9 is tuned by a shunt condenser 10 with which 65 it forms the tuned input circuit of a detector valve 25, e. g., a triode) to the positive terminal $+HT2$ of the high tension source. The detector valve 25 is arranged to detect by the method of cumulative grid rectification, the grid thereof being coupled to one end of the tuned input circuit 9, 10, through a grid condenser 26, and a grid leak 27 being connected between the grid 28 and cathode 24 thereof.

The anode 25' of this valve is connected 75

through a utilization device (e. g. a pair of telephones), or an inter-stage coupling device (e. g. the primary of an audio frequency transformer) to the point $+HT2$, and the cathode 24 is connected both to the cathode (condenser) end of the screen grid valve tuned input circuit 9, 10, and also through a resistance 36 to the negative terminal $-HT$ of the high tension source. The cathode 4 of the screen grid valve is connected both to a point $+HT1$ on the high tension source between the negative terminal thereof and the points $+HT2$, and, also, through a resistance 37 to the said point $+HT2$. A tapping point 38 on the resistance 37 is connected to the screen grid 15 which is connected to the cathode 4 through a condenser 16.

The detector valve will, in the absence of a received signal, be conductive, and its anode current will cause the grid of the screen grid valve 20 to be above earth potential (that of the negative terminal of the high tension source) by a certain amount. The point $+HT1$ is so chosen that in these circumstances the grid bias of said valve is the normal amplifying bias. When a signal 25 arrives the detector valve reduces its conductivity, and, if the signal is sufficiently strong, "cuts-off", decreasing the positive potential on the control grid of the screen grid valve (i. e. increasing the net negative bias of this valve) and 30 therefore reducing its gain.

In a modification of the last described embodiment, and illustrated in Fig. 5, a separate detector valve 39 is provided specially for gain control, its grid 40 being capacity coupled at 41 to the grid 28 of the first detector 25 and its cathode 42 being capacitatively coupled at 43 to the cathode end of the tuned input circuit 9, 10 of said first detector. The first detector 25 may operate as a bottom bend detector, the cathode end of the 40 tuned input circuit 9, 10, thereof being accordingly connected to a suitable value of bias potential at $GB-$. The second detector 39 operates by the method of cumulative grid rectification, and the cathode thereof is connected to the condenser 45 (cathode) end of the tuned input circuit 1, 2, of the screen grid valve 5, the anode 44 of said second detector being connected to a suitable positive point $+HT2$ on the high tension source.

In a still further modification illustrated in 50 Fig. 6 the screen grid valve input circuit is as described in the two last mentioned embodiments, the screen grid receives potential in exactly the same way, and the anode circuit of the screen grid valve is coupled to the tuned grid 55 circuit of a leaky grid detector valve 25 which may be the normally provided detector valve. The cathode 24 of the detector valve is however connected to the screen grid 44 of a second screen grid valve 45, and also, to the cathode 46 thereof 60 through a resistance 47. The control grid 48 of the second screen grid valve is connected to the cathode thereof; a condenser 49 is connected between anode 50 and cathode 46 thereof; the said cathode is connected to the condenser (cathode) end of the tuned grid circuit 1, 2 of the first screen grid valve 5; and the anode 50 is connected to the positive terminal $+HT2$ of the high tension source.

In a variation of this embodiment illustrated 70 in Fig. 7 a separate leaky grid detector 31 is provided for the gain control, the grid 32 of this detector being capacity coupled at 33 to the grid 28 of the first detector 25 which is no longer of the leaky grid type, and operates as a bottom bend detector having its grid circuit completed

through a bias battery (not shown but connected at $GB-$) in the normal way. The cathode of the second detector is connected to the screen grid of the second screened grid valve, the circuit in other respects being as before. In these two arrangements the advent of a received signal biases the detector (i. e. the gain control detector) towards cut-off, thereby reducing the positive potential (above earth) of the control grid of the first screened grid valve—in part by 5 reason of the decrease in current flow through the resistance between the input circuit of the first screened grid valve and the negative terminal of the high tension source, and in part by 10 reason of the decrease in the positive potential applied to the screened grid of the second screened grid valve, which last effect, of course, diminishes the anode current passed by the said second screened grid valve.

It will be noted that the control effect will be 20 increased by any screen grid current which may flow in the second screened grid valve. In another modification illustrated in Fig. 8 the first screened grid valve 5 has its cathode 4 connected to the negative terminal $HT-$ of the source 25 of anode potential and the condenser (cathode) end of its tuned input circuit connected to a suitable value of negative grid bias at $Gb-1$. The anode circuit of the valve is coupled to the 30 tuned input circuit 9, 10, of a leaky grid detector 28 adjusted to pass current in the absence of a signal and having its anode 30 connected through a pair of telephones or the like to the same point $+HT$ of positive potential as that from which the screened grid valve anode is 35 energized. The cathode of the detector is connected both to the negative terminal $HT-$ of the high tension source through a resistance 51 which is shunted by the condenser 16 and also to the screen grid 15 of the screened grid valve 5. 40

In a variation of this arrangement illustrated in Fig. 9 a separate leaky grid detector 31 is provided for the gain control, this second detector having its control grid 32 capacity coupled at 33 to the control grid of the first detector, 45 which may now be a bottom bend detector having its grid circuit completed as in the normal way through a suitable bias source connected at $GB-2$. The cathode of the second detector is connected to the screen grid of the screened grid 50 valve and, through the resistance 51 to the negative terminal of the high tension source.

The operation of these two embodiments is very similar to that of those last described, decrease in anode current of the (gain control) 55 detector occurring when signals are received, and thereby occasioning variation of the potential of the screen grid of the screened grid valve in the required direction.

If desired the control effected by the (gain control) detector in the last two described embodiments may be amplified. In one arrangement of this kind shown in Fig. 10 the first of the last two described embodiments is modified by providing a second screened grid valve 52 65 to the screen grid 53 of which the cathode of the leaky grid signal and gain control detector 28 is connected. The anode 54 of this second screened grid valve receives potential from the same point $+HT$ on the high tension source as 70 do the anodes of the other valves and the cathode 55 thereof is connected to the screen grid 15 of the first screened grid valve 5. The said cathode 55 is connected to the screen grid 15 of the valve 5, and is also connected to the control grid 75

56 of the valve 52 through a resistance 57 shunted by a condenser 58 and to the screen grid 53 thereof, and also, through a resistance 59 shunted by the condenser 16 to the negative terminal 5 —HT of the high tension source.

As before and as illustrated in Fig. 11 a separate (gain control) detector 31 having its grid capacity 32 coupled to the grid of the first detector 28 may be employed, in which case the 10 first detector may be a bottom bend detector having its grid circuit completed through a bias battery in the normal way and the cathode of the second detector 31 (instead of that of the signal detector) is connected to the screen grid 15 of the second screened grid valve 52.

Particularly good results can be obtained when in carrying out the present invention one or more of the screen grid valves employed are so-called "variable mu" valves e. g. valves as at present 20 known under the trade designation "Marconi valve VMS4" and such a valve has been utilized with very satisfactory results as the valve whose gain is automatically controlled i. e. as the "first screened grid valve" in the above described embodiments. Also, of course, indirectly heated cathode valves may be employed in carrying out 25 this invention and in some cases should be employed in order to avoid the disadvantage that, in some of the above described circuits, separate 30 cathode heating batteries would in practice be required for heating the filaments of the separate valves.

It will be noted that arrangements in accordance with the present invention offer substantial 35 practical advantages the main advantages obtained being:

- (1) Greater simplicity
- (2) Reduced number of auxiliary valves for a given result
- 40 (3) High efficiency and (in certain of the embodiments)
- (4) Avoidance of any necessity to employ auxiliary batteries.

What I claim is:—

45 1. In a radio receiver, including a radio frequency screen grid amplifier tube, an impedance in the cathode circuit of said tube, a source of potential for the electrodes of the tube, a connection from the positive terminal of the source to the tube anode, a connection from a less positive point on said source to one side of said impedance, a second impedance having one side connected to said anode and positive terminal and its other side to the cathode side of said first 50 impedance, a connection from the screen grid of said tube to an intermediate point on said second impedance, a direct current connection from the signal control grid of said tube to a point on said first impedance which is negative with respect to 55 the tube cathode, and means for varying the magnitude of said first impedance in accordance with signal amplitude variations whereby the effective potentials of the signal grid, screen grid and anode of the amplifier tube are simultaneously adjusted.

60 2. In a receiver, as defined in claim 1, said first impedance comprising a control electron discharge tube having its anode connected to the cathode of the amplifier tube and its cathode connected to the signal grid of the amplifier tube, a detector coupled to the amplifier anode circuit, and a connection between the control grid of said control tube and the space current path of the detector.

75 3. In an automatic volume control arrange-

ment for a radio receiver, which receiver includes a radio frequency screen grid amplifier and a detector, a control tube having its anode connected to the amplifier cathode and its cathode connected to the signal grid of the amplifier tube, 5 a source of potential, a connection, including a resistor, from the positive side of said source to the control tube anode, the amplifier anode and screen grid being connected to positive and less positive points respectively on said resistor, the 10 control grid of the control tube being connected in the space current path of the detector whereby variations in intensity of the latter result in impedance changes of said control tube.

4. In an arrangement, as defined in claim 3, 15 said detector including a leaky condenser network in its input circuit, and a resonant coupling means connecting the latter to the amplifier anode circuit.

5. In an arrangement, as defined in claim 1, a 20 detector, means for coupling the amplifier anode circuit to the detector input circuit, and a connection from the space current path of the detector to the said first impedance.

6. In an arrangement, as defined in claim 1, a 25 detector coupled to the amplifier, a direct current amplifier, having its input circuit coupled to the detector output circuit, and said first impedance being connected in the space current path of the direct current amplifier.

30 7. In a signal receiving system including a radio frequency amplifier of the screen grid type, a source of direct current voltage for energizing the electrodes of the amplifier, a connection between a point of positive potential of said source 35 and the anode of said amplifier, a resistor connected between the screen grid of said amplifier and the cathode thereof, and a direct current path connected between said positive potential point and a point of said source which is at a 40 substantially lower potential than said first point, said path including an impedance arranged in series with said resistor, and means for automatically varying the magnitude of said impedance 45 in response to received signal amplitude variations whereby the effective operating voltage of said screen grid is dependent upon the magnitude of said impedance.

8. In a signal receiving system including a radio frequency amplifier of the screen grid type, a 50 source of direct current voltage for energizing the electrodes of the amplifier, a connection between a point of positive potential of said source and the anode of said amplifier, a resistor connected between the screen grid of said amplifier and the cathode thereof, and a direct current path 55 connected between said positive potential point and a point of said source which is at a substantially lower potential than said first point, said path including an impedance arranged in series 60 with said resistor, and means for automatically varying the magnitude of said impedance in response to received signal amplitude variations whereby the effective operating voltage of said screen grid is dependent upon the magnitude of 65 said impedance, said impedance comprising the internal tube impedance of an electron discharge tube connected between the cathode of said amplifier and said second potential point.

9. In a signal receiving system including a radio 70 frequency amplifier of the screen grid type, a source of direct current voltage for energizing the electrodes of the amplifier, a connection between a point of positive potential of said source and the anode of said amplifier, a resistor connected 75

- between the screen grid of said amplifier and the cathode thereof, and a direct current path connected between said positive potential point and a point of said source which is at a substantially lower potential than said first point, said path including an impedance arranged in series with said resistor, and means for automatically varying the magnitude of said impedance in response to received signal amplitude variations whereby the effective operating voltage of said screen grid is dependent upon the magnitude of said impedance, and said varying means comprising a signal rectifier.
10. In an electrical wave transmission system which includes a transmission tube provided with at least a cathode, a wave input electrode, output electrode, and an auxiliary electrode disposed be-
- tween the input and output electrodes, a source of direct current voltage for energizing the tube electrodes, a connection between a point of positive potential of said source and the transmission tube output electrode, an impedance connected between the said auxiliary electrode and the cathode, a direct current path between said positive potential point and another point of said source which is at a substantially lower potential, said path including an impedance arranged in series with the first impedance, and means for adjusting the magnitude of the said second impedance in response to wave amplitude variations whereby the effective operating voltage of said auxiliary electrode is dependent upon the magnitude of said second impedance.
15. REGINALD BASIL ARMSTRONG.
